CLAIM

The ornamental design for an inflatable rescue bag, as shown and described.

DESCRIPTION

FIG. 1 is a front, left side, and top perspective view of the first embodiment of an inflatable rescue bag showing our new design in a closed/zipped and uninflated condition; FIG. 2 is a front and bottom perspective view thereof; FIG. 3 is a top view thereof; FIG. 4 is a bottom view thereof; FIG. 5 is a left side view thereof; FIG. 6 is a right side view thereof; FIG. 7 is a rear view thereof; FIG. 8 is a front view thereof; FIG. 9 is a second front and top perspective view thereof with the zipper in an open/unzipped position; FIG. 10 is a third front and top perspective view thereof in a closed/zipped and inflated condition; FIG. 11 is a front and bottom perspective view of the bag of FIG. 10; FIG. 12 is a top view of the bag of FIG. 10; FIG. 13 is a bottom view of the bag of FIG. 10; FIG. 14 is a left side view of the bag of FIG. 10; FIG. 15 is a right side view of the bag of FIG. 10; FIG. 16 is a rear view of the bag of FIG. 10; and, FIG. 17 is a front view of the bag of FIG. 10. The broken line showing of the inflatable rescue bag, including the interior area of FIG. 9 that is surrounded by broken line, is for the purpose of illustrating portions of the article that form no part of the claimed design.

1 Claim, 17 Drawing Sheets
